UNITED STATES PATENT OFFICE

2,468,318

ROTARY RETORT

James Kean Young, Maylands, and Ernest Archibald Wright, Perth, Western Australia, Australia.

Application October 23, 1947, Serial No. 781,516.

4 Claims. (Cl. 285—97.1.)

1

This invention relates to an improved rotary retort.

In using the ordinary type of rotary retorts in the distillation of carbonaceous materials, major difficulties are encountered when there are one or both of the following conditions:

A. Hot and/or varying temperatures — the resulting heat and/or changes in expansion causing undue wear of the gland packing and/or "seizing" of the retort with consequential damage.

B. Injurious gas — causing disastrous wear of the gland packing and/or "gumming" up or fouling of the gland packing which may result in "seizing" or stopping of the retort with consequential damage.

The foregoing disadvantages and other associated difficulties are overcome by the use of the retort the subject of this application.

The invention consists broadly of a rotary retort which has a gland comprising a long collar of somewhat greater diameter than the retort, and being connected thereto so as to form an air jacket between the collar and the retort, a circumferential trough being formed on the collar for the reception of cooling water.

The end of the collar connected to the retort is unavoidably subject to considerable expansion while the other end, being cooled by the flow of water in the circumferential trough assisted by the presence of the air jacket, is not subject to appreciable expansion. At an appropriate intermediate position the packings of the gland are situated. Obviously the collar must be of sufficient length to avoid undue stress due to the difference in amount of expansion at different points along the collar.

The invention will readily be understood by reference to the accompanying drawing which is a longitudinal sectional elevation thereof.

As shown in this drawing, the retort 10, as usual in such apparatus, passes through a heating and combustion chamber 11 in which the retort is heated externally. The retort is as usual inclined slightly toward the discharge end. At such end the retort passes through the combustion chamber 11 into a stationary discharge compartment 12, where a gland is necessarily provided. There are spider supports 13 inside the retort near the discharge end, and these centrally carry a shaft 14 which extends out through the far side of the discharge compartment 12 and is supported in bearings 15 and by a thrust bearing 16 so that the retort cannot expand longitudinally in this direction.

The expansion of the retort is provided for at

the higher end where a reduced extension passes through the combustion chamber and is supported on bearings 17 that allow expansion, and where it has a spur wheel 18 driven by a wide pinion 19 which also allows for such expansion. The means for feeding the retort and for the discharge of the products of combustion may be as is common to this type of apparatus.

At the discharge end the retort is connected to a long collar 20 which is of somewhat greater diameter than the retort and which is suitably connected thereto, such as by welding, at the end. In consequence, there is an air jacket between the retort 10 and the collar 20. Near the unattached end of the collar 20 is formed a circumferential trough 21 into which cooling water can be run during operation. At an appropriate intermediate position a flat ring 22 can be welded or otherwise connected to the collar 20 to form the actual bearing face of the gland, and this is in juxtaposition to an appropriate ring or bearing face 23 on the stationary discharge compartment 12. There will be a shoulder on such ring or bearing face against which asbestos or other heat-resisting fibre can be packed. In association with the ring 23 there will also conveniently be a circular channel member 25 which is supplied with a source of steam or other suitable fluid through a pipe 26. On the far side of the channel member 25 another ring of packing material can be provided, and against this is adapted to be held the face of the gland ring 27, which can be tightened in the normal manner.

As a result of the construction described, longitudinal expansion takes place at the high end where there is provision for it being accommodated, and there is very little longitudinal movement at the discharge end where the main gland is situated. Further, at the actual gland relatively cool conditions are prevailing because the collar member 20 is only connected to the retort 10 at one end, and moreover is cooled with water as it rotates. Further, the use of the steam or other suitable fluid not only has a cooling effect, but creates a positive pressure in the locality of the gland which stops the products of distillation or combustion from escaping.

We claim:

1. In a rotary retort a gland member at an end thereof comprising a long collar of greater diameter connected to the retort so as to form an air jacket between the collar and the retort; and a circumferential trough formed on the collar to act as a channel for cooling water.
2. In a rotary retort a gland at an end there-

of consisting of a long collar of greater diameter than that of the retort said collar being connected to the retort so as to form an air jacket between the collar and the retort; a circumferential trough formed on the collar to act as a channel for cooling water; a compartment into which the end of the retort projects; a bearing ring in the compartment in juxtaposition to the collar connected to the retort; a gland ring connected to the compartment; and packing held in position by the gland ring so as to form a joint between the collar and the bearing ring on the compartment.

3. In a rotary retort a gland at the end thereof consisting of a long collar of greater diameter than that of the retort said collar being connected to the retort so as to form an air jacket between the collar and the retort; a circumferential trough formed on the collar to act as a channel for cooling water; a bearing ring connected to the collar; a stationary discharge compartment into which the end of the retort projects; a bearing ring in the stationary compartment in juxtaposition to the bearing ring on the collar connected to the retort; a gland ring connected to the stationary member; and packing held in position by the gland ring so as to form a joint between the bearing ring on the collar and the bearing ring on the stationary member.

4. In a rotary retort a gland at the end thereof consisting of a long collar of greater diameter than that of the retort said collar being connected to the retort so as to form an air jacket

between the collar and the retort; a circumferential trough formed on the collar to act as a channel for cooling water; a bearing ring connected to the collar; a stationary discharge compartment into which the end of the retort projects; a bearing ring in the stationary compartment in juxtaposition to the bearing ring on the collar connected to the retort; a circular channel member associated with the bearing ring on the stationary member; a pipe connection to the circular channel member to supply fluid under pressure; a gland ring connected to the stationary member; and packing held in position by the gland ring so as to form a joint between the bearing ring on the collar and the bearing ring on the stationary member.
